UNITED STATES PATENT OFFICE.

HERBERT E. ELLSWORTH, OF CLEVELAND, OHIO.

DESIGN FOR AN ADVERTISING-STAND.

No. 38,395.

Specification for Design.

Patented Jan. 1, 1907.

Application filed October 8, 1906. Serial No. 338,089. Term of patent 7 years.

To all whom it may concern:

Be it known that I, HERBERT E. ELLSWORTH, a citizen of the United States, residing at Cleveland, county of Cuyahoga, State of Ohio, have invented a new, original, and ornamental Design for an Advertising-Stand.

This design is illustrated in the accompanying drawing, showing a perspective view of the stand.

I claim—

The ornamental design for an advertising-stand, as shown.

HERBERT E. ELLSWORTH.

Witnesses:

WM. M. MONROE,
GEO. S. COLE.
